DESIGN FOR A DRAWER PULL

Cornell D. Hazenberg, Evansville, Ind.

Application March 21, 1938, Serial No. 75,982

Term of patent 3½ years

To all whom it may concern:

Be it known that I, Cornell D. Hazenberg, a citizen of the United States and a resident of Evansville, county of Vanderburg, and State of Indiana, have invented a new, original, and ornamental Design for a Drawer Pull, of which the following is a specification, reference being had to the accompanying drawing, forming part thereof.

In the drawing, Fig. 1 is a top plan view of a drawer pull, showing my design; Fig. 2 is a front elevational view, and Fig. 3 is a perspective view.

I claim:

The ornamental design for a drawer pull, as shown.

CORNELL D. HAZENBERG.
